DESIGN FOR A GLIDER

William I. Smith, Goshen, Ind., assignor to The Hettrick Manufacturing Company, Toledo, Ohio, a corporation of Ohio

Application January 4, 1941, Serial No. 97,814

Term of patent 7 years

To all whom it may concern:

Be it known that I, William I. Smith, a citizen of the United States and a resident of Goshen, Elkhart County, Indiana, have invented a new, original, and ornamental Design for a Glider, of which the following is a specification, reference being had to the accompanying drawing, forming a part thereof.

In the drawing the figure is a perspective view of a glider, showing my new design.

The characteristic features of my design reside in a glider having a supporting frame provided with laterally spaced uprights and a structure carried by and spaced inwardly from the uprights, the structure including individually spaced apart seat and back units, all as shown.

I claim:

The ornamental design for a glider, as shown and described.

WILLIAM I. SMITH.
